Primary Examiner — Cynthia Ramirez*Assistant Examiner* — Darcy Fabre(74) Attorney, Agent, or Firm — Todd R. Fronek; Larkin Hoffman Daly & Lindgren, Ltd.(57) CLAIM

The ornamental design for a post-surgical bra as shown and described.

DESCRIPTION

FIG. 1 is a front view of a post-surgical bra of the present design;

FIG. 2 is a front view of the post-surgical bra of FIG. 1 with a zipper being partially unzipped;

FIG. 3 is a rear view of the post-surgical bra of FIG. 1;

FIG. 4 is a front view of a second embodiment of a post-surgical bra of the present design; and,

FIG. 5 is a front view of the post-surgical bra of FIG. 4 with a zipper being partially unzipped.

The broken lines in the figures show portions of the post-surgical bra which form no part of the claimed design.

1 Claim, 5 Drawing Sheets(56)
